ARTIFICIAL TEETH

Simon Myerson, Newton, Mass., and Victor H. Sears, Salt Lake City, Utah, assignors to Myerson Tooth Corporation, Cambridge, Mass., a corporation of Massachusetts

Filed Feb. 7, 1957, Ser. No. 638,809
8 Claims. (Cl. 32—2)

The present invention relates to artificial dental restorations, especially artificial teeth and artificial dentures and bridgework containing the same.

Many dentists prefer artificial dentures having plastic teeth because they are believed to reduce shock and trauma on the supporting tissues and they are more perfectly and comfortably adjusted to the patient's articulation during wear. They are also easier to adapt by the technicians in numerous cases. However, plastic posterior teeth, especially of the type having modified occlusal forms, suffer loss of efficiency and functional structure by wear. By "modified occlusal forms" we refer to those forms which depart from the cusp formation of natural teeth, as for example, the tooth described in U.S. Myerson Patent 1,879,419. For convenience, we shall hereinafter refer to such type of teeth as "functional posteriors." Moreover, many patients find it more difficult to chew certain types of food with plastic than with porcelain teeth.

One of the objects of this invention is to combine the advantages of hard, dense, wear resistant, ceramic teeth with those of plastic teeth in upper and lower dentures, while at the same time reducing the disadvantageous effects of each by providing one of the pair of upper and lower dentures with porcelain posterior teeth having a particular novel and improved occlusal surface construction and the other of such pair of upper and lower dentures with plastic posterior teeth, also having such particular, novel and improved occlusal surface construction. Another object is to provide a novel and improved occlusal surface construction for artificial teeth, especially posterior teeth, which reduces loss by wear by a substantially greater amount than other occlusal surface constructions, as for example that described in Patent No. 1,879,419, when porcelain teeth of one of a pair of dentures are opposed to plastic teeth of the other. Although the occlusal structure of the posterior teeth of this invention has special benefits for use in upper and lower posteriors in which one set of posterior teeth are porcelain and the opposite are plastic, it has many advantages when used in the conventional manner, i.e. porcelain articulated with porcelain or plastic articulated with plastic. One of the objectionable features inherent in artificial dentures is a tendency toward tilting on one side while chewing on the other side, e.g. the right side of the lower denture rises when stress is applied to the left, or the upper right side comes down. Dentures also have a tendency under certain circumstances to slide forward and backward on their supports. It is an object of this invention to stabilize dentures against these dislocating forces. It is another object of the present invention to provide functional posterior teeth, which are economical to produce, which are easy to handle by the dental technician and which by their novel and improved occlusal surface structure will direct the forces of mastication so as to stabilize the artificial dentures against tilting and sliding and protect the cutting area from wear and breakage and which have the above mentioned further advantages when teeth of one denture are porcelain and those of the opposing denture are plastic. Yet another object is to provide an artificial tooth having an improved occlusal surface construction. Other and further objects and advantages of the invention will be pointed out hereinafter in the fol-

2

lowing and more detailed description and by reference to the accompanying drawings in which:

FIG. 1 is a front view of a pair of upper and lower dentures embodying the present invention and mounted in what is termed centric relation on casts corresponding in shape to a human mandible and maxilla.

FIG. 2 is a side view of the dentures of FIG. 1;

FIG. 3 is a view in perspective of a lower first molar of the lower denture of FIGS. 1 and 2 showing the occlusal construction of the present invention applied to a molar;

FIG. 4 is a perspective view of the lower first molar of FIG. 3 taken at a different angle;

FIG. 5 is a view in perspective of a lower second bicuspid of the lower denture of FIGS. 1 and 2 showing the occlusal construction of the present invention applied to a bicuspid;

FIG. 6 is a view in perspective of the upper denture of FIGS. 1 and 2 showing the occlusal construction of the present invention applied to four upper posterior teeth on each side of the upper denture;

FIG. 7 is a lateral section taken along the line 7—7 of FIGS. 1 and 2.

All the upper teeth are porcelain and all the lower teeth are plastic. This order may be reversed. Moreover, the anterior teeth of both upper and lower dentures may be made of plastic or porcelain without materially affecting the efficiency or the durability of the denture.

The teeth herein described and illustrated have many advantages over teeth presently available whether they are all made of porcelain or all made of plastic and whether the opposing teeth are of like or different materials. However, if plastic teeth are opposed to porcelain teeth, as illustrated in FIGS. 1 to 7, the most important advantages of porcelain as well as those of plastic will be preserved and the disadvantages of each are reduced.

In the combination shown in FIGS. 1 to 7 in which plastic is opposed to porcelain loss by wear is so far reduced as to be negligible, in fact, probably beneficial.

Loss by wear was determined by two means. First the dentures were processed in the usual manner and closely adapted to articulation in the patient's mouth by spot grinding the high spots. As nearly as possible all grinding was done on the plastic teeth. Any areas ground on the porcelain teeth were carefully repolished. After one week of wear final adjustment was made orally and casts of the dentures were then made from time to time. By this means, a check on the clinical wear was made. The second method was by use of a machine which rubbed opposing teeth against each other in a mild abrasive mix under carefully controlled conditions. This machine has been in use for a period of years to determine wear of plastic teeth and has been found thoroughly reliable. When plastic teeth of the type described in U.S. Patent No. 1,879,419 were rubbed against each other the wear loss was considerably greater than when one of the teeth was porcelain and the other plastic. When plastic and porcelain teeth having the occlusal construction of the present invention were rubbed against each other in the same test, the wear loss was markedly less than that of the plastic and porcelain teeth having the construction of Patent No. 1,879,419.

With reference to the figures, 1 is a porcelain upper first molar, 2 is a porcelain upper second molar, 3 is a porcelain upper second bicuspid and 4 is a porcelain upper first bicuspid, all of which are mounted in the upper denture base member 5 which is in turn mounted on the upper or maxillary cast 6. Correspondingly, 7 is a plastic lower first molar, 8 is a plastic lower second molar, 9 is a plastic lower second bicuspid and 10 is a plastic lower first bicuspid all of which are mounted in a lower denture base member 12 which is in turn mounted on

the lower cast 14. 15 represents the distal side of each tooth (see FIGS. 2 to 5), 19 is the mesial side, 21 the buccal side and 23 the lingual side. The occlusal surface of each of the teeth is characterized by a narrow buccal cutting margin 16 of a buccal cutter 17 (see FIGS. 3 to 7), a broad, flat, lingual crushing area 18, two transverse wedge-shaped cutters 20 in the case of the molars and a single transverse wedge-shaped cutter 20 in the case of the bicuspids connecting the buccal cutting margin 16 and the flat lingual crushing area 18 and clearance channels 22 for the escape of the masticated food from the depressed areas 24 formed by the sloped side walls of the cutters and crushing area. The buccal cutting margin 16, the cutting margins 26 of the transverse wedge-shaped cutters 20 and the flat crushing area 18 are preferably all in one occlusal plane so as to assure unhindered motion when in articulation with the opposite teeth. The mesial buccal margins of the first upper bicuspid 4 and the mesial and distal margins of the first lower bicuspid 10 may be slightly beveled without interfering with free motion of the mandible since the mandible normally does not retrace in mastication. Moreover, when the dentures are finished and the plane of occlusion established the molars and bicuspids may be altered to give them a cusp-like appearance. In some cases this may be advisable in order to further decrease the stress of closing the dentures through food. However, it appears best to make this modification when indicated and after the dentures are processed. The transverse cutters 20 preferably extend from the buccal cutter margin 16 in a distal and lingual direction to the crushing area 18 in one set, e.g. the lower teeth, and in a mesial lingual direction in the opposite set, e.g. the upper teeth.

FIG. 6 shows a set of four upper posterior teeth with a line 29 running from the distal of the second molar to the mesial of the first bicuspid substantially mid-way between the buccal and lingual margins of the teeth. We will call the line 29 the "occlusal median axis." By referring to this line, it will be seen that the buccal cutting margins 16 and the major portion of the transverse cutting margins 26 are buccal to this median occlusal axis and that the crushing areas 18 are lingual to and preferably do not cross this axis. The axis usually lies in the same vertical plane as the highest portion or apex of the mandibular ridge 34, if the teeth are set up as usually recommended in relation to the ridge and as illustrated in FIGURES 6 and 7. The apex of the ridge on one side is designated as 30 and on the other side as 30a. The maxillary ridge is designated as 36, its apex on one side is designated as 32 and the other as 32a. Consequently, the lingual crushing area 18 will usually be located lingually of 30 and 30a and lingually of 32 and 32a. The forces exerted on the occlusal surface of the teeth during mastication are imparted to the maxilla and mandible through these ridges, the apical areas of which may be considered as support fulcrums for the dentures. What we have termed apical areas are often referred to as the crest or center of the ridge. Preferably, the lingual flat crushing area 18 of each tooth reaches substantially to the occlusal median axis so that it occupies substantially the entire lingual half of the occlusal surface of the tooth. It is preferably three times or more broader than the cutting margin 16 and the cutting margin 26 especially in the first molar and second bicuspid teeth. The area thereof is preferably more than twice the sum of the areas of the cutter margins 16 and 26 of each tooth. However, so long as the crushing area 18 of the tooth is substantially larger than the sum of the cutting margin areas 26 and 16 thereof and is substantially broader than the cutter margin 16 and the cutting margin 26 the advantages of the present invention are obtained. In effect, the areas of the cutting margins 16 and 26 of each tooth together with the crushing area 18 comprise the masticating area of the occlusal surface of the tooth and the crushing area 18 is the largest and

broadest portion of the masticating area. Since the flat lingual crushing areas 18 are substantially larger and broader than the cutting margin areas it requires greater pressure to force them through the food than do the cutters. Consequently, if the teeth are correctly positioned by the technician the greatest forces during mastication will be applied to the dentures and thence to the supporting fulcrums 30, 30a, 32 and 32a at and by means of the crushing areas 18 directly over or lingual 5 of the apical areas of the ridges as shown at 42 in FIG. 7. The dentures are thereby stabilized against tilting on the support fulcrums just as any load applied to a board 44 (FIG. 7) between two support fulcrum points 30 and 30a of the board as at 42 will not tilt the board and any 10 load applied to the board outside these points as at 40 will tend to do so. So long as a relatively large, broad crushing area is provided in the occlusal plane lingual of the vertical extension of the fulcrum portions 30, 30a, 32 and 32a of the dental ridges, as compared to the masticating areas in the occlusal plane buccal of such fulcrum 15 portions, the forces of mastication will tend to stabilize the dentures.

The stress during mastication is also centralized from the front to back in the first molar and second bicuspid 25 area by making the flat crushing area 18 of each of these teeth 1 and 3 larger, preferably 50% or more larger, than the flat area of each first bicuspid and second molar as illustrated in FIG. 6. This causes the greatest force during mastication to be exerted in these areas of 1 and 3 30 which are central with respect to the front and back of the dentures whereby front to back sliding of the dentures is inhibited.

Preferably the surface of the porcelain teeth should be 35 smooth and capable of being repolished to a high degree of smoothness after grinding thereof. Porcelain teeth made in accordance with the method described in U.S. Patent No. 2,724,166 are satisfactory. The plastic teeth preferably comprise cross linked copolymers, known in the art to be resistant to solvents and useful for making 40 plastic teeth. One such copolymer is a cross linked copolymer of methyl methacrylate.

Although we have described our tooth and its use in 45 relation to dentures, it may also be used in other dental restorations, e.g. in bridgework. It is possible to vary the structures described and illustrated without departing from the spirit of this invention. The term "occlusal median axis" as used herein refers to a mesial distal line 50 passing approximately through the middle of the occlusal surface (approximately midway between the buccal and lingual edges of such surface) as illustrated in FIG. 6 by the line 29.

The imaginary line which lies on the occlusal surface of each of the four posterior teeth illustrated in FIG. 6 will lie approximately in the same vertical plane as the 55 apex, or "crest," of the ridges, as they are often termed, if the teeth are set up as usually advocated, over the "center" or crest of the ridge and as illustrated in FIG. 6 wherein the teeth have been set up in soft wax on a denture base plate in the preparation of a trial denture 60 and as illustrated in the finished upper and lower dentures in FIG. 7. It is often necessary to depart from the ideal positioning of the teeth in relation to the dental ridges; even in these cases, the stability of the dentures will be improved by the use of the teeth of this invention 65 wherein the largest and broadest portion of the masticating area of the tooth is located along the occlusal lingual margin of the tooth.

While setting up posterior teeth usually includes two 70 molars and two bicuspids on each side there are numerous occasions when one or more teeth are eliminated.

In the claims which follow, the contacting occlusal surfaces which comprise the crushing areas and the cutting areas of the tooth will be referred to as the masticating 75 areas.

We claim:

1. An artificial tooth having a flat crushing area and a cutting area on its occlusal aspect, the said crushing area being of generally segmental shape substantially broader than the cutting area and being located along the lingual occlusal margin of the tooth, said crushing area being mainly lingual of the median occlusal axis of the tooth and said cutting area mainly buccal of said axis, said cutting and crushing areas lying substantially in the same plane.

2. An artificial tooth according to claim 1 wherein said crushing area comprises approximately 50% of the occlusal surface of the tooth.

3. An artificial tooth having a crushing area and cutting area on its occlusal aspect, the said crushing area being substantially broader than the cutting area and being located along the lingual occlusal margin of the tooth, said cutting area comprising a buccal cutting margin and a transverse cutter extending between the buccal cutting margin and the said crushing area.

4. An artificial tooth having a crushing area and cutting area on its occlusal aspect, the said crushing area being substantially broader than the cutting area and being located along the lingual occlusal margin of the tooth, said cutting area comprising a buccal cutting margin and a transverse cutter extending between the buccal cutting margin and the said crushing area, and a groove to clear the masticated food from the occlusal face of the tooth, said cutting area lying substantially in a plane extending substantially from the mesial to the distal side of the tooth.

5. An artificial tooth having a crushing area and cutting area on its occlusal aspect, the said crushing area being substantially broader than the cutting area and being located along the lingual occlusal margin of the tooth, said cutting area comprising a buccal cutting margin and a transverse cutter margin extending between the buccal cutting margin and the said crushing area, said buccal cutting margin, transverse cutting margin and crushing area lying in substantially the same plane.

6. In a combination in an upper and lower denture, an upper posterior tooth and an opposing lower posterior tooth, each of which has a masticating area comprising a crushing area and a cutting area on its occlusal aspect, the crushing area comprising the broadest portion of the masticating area and being located along the lingual occlusal margin of the tooth, one of said posterior teeth being of smooth dense porcelain and the other of a plastic material.

10 7. An artificial tooth having a flat crushing area and a cutting area on its occlusal aspect, said crushing area being of generally segmental shape substantially broader and larger than the cutting area and being located along the lingual occlusal margin of the tooth, said cutting area comprising the buccal cutting margin of said tooth and being substantially flat in a mesial-distal direction and lying in substantially the same plane as said crushing area.

8. An artificial tooth having a substantially flat crushing area and a cutting area on its occlusal aspect, the said crushing area being substantially broader and larger than the cutting area and being located along the lingual occlusal margin of the tooth, said cutting area comprising a buccal cutting margin, said cutting area being substantially flat in a mesial-distal direction and lying substantially in the same plane as said crushing area, said flat crushing area being broader and larger than said cutting area in the buccal-lingual direction along at least the major portion of the dimension of the occlusal aspect 30 of the tooth in the mesial-distal direction.
